GLOVE

Fred Tatar, Gloversville, N. Y.

Application October 29, 1946, Serial No. 706,465

7 Claims. (Cl. 2—169)

1

This invention relates to improvements in gloves and particularly relates to improvements in blanks or trunks for gloves and to thumb and forefinger constructions therefor.

An object of the invention is to provide a glove in which the back portion of the thumb is formed integrally with the palm portion whereby great economy of material is effected.

Another object of the invention is to provide a glove in which the tip of the thumb and the base of the thumb are seamless thereby imparting greater strength and durability to the glove.

A further object of the invention is to provide a glove in which the back portion of the thumb is formed of material which is conventionally and normally cut away to provide an opening to which the thumb piece is sewn.

Another object of the invention is to provide a glove which will have enhanced visual appeal through the use of longer lines and which may be fabricated with economy of labor and material.

Further objects and advantages of the invention will readily appear from the following description of a preferred embodiment of the invention taken in connection with the accompanying drawings, wherein

Fig. 1 is a plan view of the main trunk which may be employed in making a glove.

Fig. 2 is a plan view of an auxiliary piece or trunk which becomes the front portion of the forefinger of the finished glove.

Fig. 3 is plan view of another auxiliary piece or trunk which becomes the front portion of the thumb of the finished glove.

Fig. 4 is a front plan view of a finished glove formed from the trunks illustrated in Figs. 1-3 and with the thumb piece bent back to show the relation of the assembled trunks.

Fig. 5 is a front plan view of the glove similar to Fig. 4 but with the thumb in its normal extended position.

Fig. 6 is a perspective view of a right-handed main trunk similar to that shown in Fig. 1 folded along its vertical, longitudinal fold line and with the auxiliary forefinger trunk attached thereto.

Fig. 7 is a vertical sectional view along line 7—7 of Fig. 6.

The main trunk or blank of the glove is indicated at 10 and is preferably a unitary piece comprising a palm portion 11 and a back portion 12. The respective finger portions of the palm portion 11 are indicated at 1, 2, 3 and 5 and the corresponding back finger portions of the back portion 12 are indicated at 1', 2' and 3'; the numeral 4' representing the back portion of the

2

forefinger. Palm portion 11 is slit deep along a line coinciding with the inner lateral edge of the third finger portion to define a free inner edge 3d adjacent finger portion 5.

An important feature of the invention is the provision of a glove having a thumb piece which is seamless at the tip thereof and whose back portion is formed integrally with the palm portion of the main trunk. Accordingly, finger portion 5, which becomes the back and side portion of the thumb in the finished glove, is cut having a free square edge E and is inwardly notched or cut away on both of its lateral edges at a point below edge E to form two thumb sections 5a and 5b symmetrical about the fold line F. Fold line F is located at approximately one-half the length of finger portion 5 measured along its outer lateral slit-edge 5c from free edge E, it being noted in this connection that the inner lateral slit-edge 5d of finger portion 5 is longer than said outer edge and is cut deeper into palm portion 11 for a purpose to be hereinafter indicated.

In forming the glove upper thumb section 5a of finger portion 5 is folded back along fold line F which becomes the tip of the thumb and the main trunk 10 is folded along fold line 13 which is coincident with the outer lateral slit-edge 5c of finger portion 5.

The auxiliary forefinger trunk 4 illustrated in Fig. 2 is an elongated piece having a square edge E' at one end and a rounded edge R at its other end. Square edge E' of auxiliary trunk 4 is joined to square edge E of thumb section 5a of the main trunk 10 by stitching, it being understood that thumb section 5a is to be folded back along fold line F as clearly shown in Figs. 6 and 7. Thus, after main trunk 10 has been folded along line 13 with auxiliary trunk 4 stitched to thumb section 5a in the manner just described, the auxiliary trunk 4 becomes the front portion of the forefinger of the finished glove.

Side edges 14 and 14a of the main trunk 10 are stitched together and the outer lateral edge of forefinger trunk 4 is stitched to the respective outer lateral edge of finger portion 4' of main trunk 10. The inner side of the forefinger of the glove may be provided with a conventional fourchette (not shown) to which the upper portion of the inner lateral edge of trunk 4 may be stitched, the lower portion of said lateral edge being stitched to the free inner edge 3d of palm portion 11 which is coincident with the inner lateral edge of finger portion 3 as clearly shown in Fig. 6. The outer lateral edge of thumb section 5a is stitched to the corresponding edge 5c of

thumb section 5b to form the back of the thumb.

The inner side of the little finger may also be provided with the usual fourchette and the remaining two fingers of the glove may similarly be provided with conventional fourchettes (not shown) to the front and back portions of which the respective lateral edges of finger portions 2 and 3 of palm portion 11 and finger portions 2' and 3' of back portion 12 may be stitched.

In order to complete the thumb portion of the glove, a preferably diamond-shaped trunk 5', illustrated in Fig. 3, is employed. Trunk 5', which may vary in shape and which may have rounded or pointed ends, becomes the face of the thumb in the completed glove, being stitched along one side to the inner edge 5d of thumb section 5b and being stitched along its other side to the inner edge of thumb section 5a uppermost and to the lower portion of the free inner edge 3d of palm portion 11 lowermost. Thumb trunk portion 5' is wider medially than at its extremities in order to give proper configuration and smooth fit to the thumb and to freely allow for the normal range of movement of the thumb.

While the drawings and the foregoing description have indicated the use of a separate trunk 4 forming the front of the forefinger in the finished glove, it is quite possible to cut the main trunk 10 with a forefinger portion integral with thumb section 5a and foldable along a suitably disposed fold line. However, this would result in wastage of material and the provision of a separately cut forefinger trunk 4 is desirable in the interest of economy of material.

It is obvious that the particular shape and size of the main trunk 10, the auxiliary front forefinger trunk 4 and the auxiliary front thumb trunk 5' may be modified for use in men's, women's and children's gloves. The aforementioned trunks may be cut from all kinds of leather as well as fabrics such as cotton, rayon or other material.

Since certain additional modifications may be made in the component trunks and finished gloves of my invention without departing from the scope thereof, it is intended that all matter contained in the foregoing description and shown in the accompanying drawings be interpreted merely as illustrative and not in a limiting sense.

By the "front portion of the thumb" as used in the foregoing specification and annexed claims is meant that portion of the thumb extending downwardly from the tip of the thumb across the ball of the thumb to the base of the thumb.

The "side and back portion of the thumb" as used in the specification and claims refers to the remaining portion of the thumb not included in the definition of the foregoing paragraph.

I claim:

1. A glove comprising a main trunk having integral palm and back portions provided with front and back finger portions, said palm portion having an innermost finger portion inwardly notched on both of its lateral edges and symmetrically bendable about a fold line to form the side and back portions of the thumb of the finished glove, said thumb portions being located wholly within said main trunk, the tip of the thumb being seamless, an auxiliary front forefinger trunk joined to the free edge of said innermost finger portion and a front thumb trunk joined to said back portion of the thumb.

2. A glove comprising a main trunk having integral palm and back portions provided with front and back finger portions, said palm portion

having an innermost finger portion inwardly notched on both of its lateral edges and symmetrically bendable about a fold line to form the side and back portions of the thumb of the finished glove, the tip of the thumb being seamless, an auxiliary front forefinger trunk joined to the free edge of said innermost finger portion and a diamond-shaped front thumb trunk joined to said back portion of the thumb along three

10 of its edges and joined along its fourth edge to said palm portion.

3. A trunk for a glove, said trunk having integral palm and back portions provided with front and back finger portions, said palm portion 15 being slit deep along a line coinciding with the inner lateral edge of the third finger portion thereof to define a free inner edge and an innermost finger portion, said innermost finger portion of the palm portion having a free square edge and being inwardly notched on both of its 20 lateral edges at a point below said square edge to form upper and lower thumb sections symmetrical about a fold line defining the tip of the thumb, said thumb sections being located wholly 25 within the body of the trunk adjacent the finger portions thereof.

4. A glove comprising a main trunk having integral palm and back portions provided with front and back finger portions, said palm portion 30 being slit deep along a line coinciding with the inner lateral edge of the third finger portion thereof to define a free inner edge and an innermost finger portion, said innermost finger portion of the palm portion having a free square edge 35 and being inwardly notched on both of its lateral edges at a point below said square edge to form upper and lower thumb sections symmetrical about a fold line defining the tip of the thumb, an auxiliary front forefinger trunk 40 joined to the free square edge of said innermost finger portion and a front thumb trunk joined to said upper and lower thumb sections and to said free inner edge of the palm portion.

5. A glove comprising a main trunk having integral palm and back portions provided with front and back finger portions, said palm portion being slit deep along a line coinciding with the inner lateral edge of the third finger portion thereof to define a free inner edge and an innermost 45 finger portion, said innermost finger portion of the palm portion having a free square edge and being inwardly notched on both of its lateral edges at a point below said square edge to form upper and lower thumb sections symmetrical 50 about a fold line defining the tip of the thumb, said thumb sections being located wholly within the main trunk, an auxiliary front forefinger trunk joined to the free square edge of said innermost finger portion and a front thumb trunk joined to said upper and lower thumb sections and to said free inner edge of the palm portion, said front thumb trunk being wider medially than at its extremities.

6. A glove comprising a main trunk having integral palm and back portions provided with front and back finger portions, said palm portion being slit deep along a line coinciding with the inner lateral edge of the third finger portion thereof to define a free inner edge and an innermost finger portion, said innermost finger portion of the palm portion having a free square edge and being inwardly notched on both of its lateral edges at a point below said square edge to form upper and lower thumb sections symmetrical 70 about a fold line defining the tip of the thumb,

an auxiliary front forefinger trunk joined to the free square edge of said innermost finger portion and a diamond-shaped front thumb trunk joined to said upper and lower thumb sections and to said free inner edge of the palm portion.

7. A glove comprising a main trunk having integral palm and back portions provided with front and back finger portions, said palm portion being slit deep along a line coinciding with the inner lateral edge of the third finger portion thereof to define a free inner edge and an innermost finger portion, said innermost finger portion of the palm portion having a free square edge and being inwardly notched on both of its lateral edges at a point below said square edge to 10 form upper and lower thumb sections symmetrical about a fold line defining the tip of the thumb, said upper and lower thumb sections becoming 15 the side and back portion of the thumb in the

completed glove, an auxiliary front forefinger trunk joined to the free square edge of said innermost finger portion and an auxiliary thumb trunk joined to said upper and lower thumb sections and to said free inner edge of the palm portion to complete the thumb of the glove, said auxiliary thumb trunk being wider medially than at its extremities.
